[57] CLAIM

The ornamental design for a lamp-reflector module for use in a motor vehicle headlighting system, as shown and described.

DESCRIPTION

FIG. 1 is a front perspective view of a lamp-reflector module for use in a motor vehicle headlighting system, illustrating our new design;

FIG. 2 is a front elevational view thereof on a slightly larger scale;

FIG. 3 is a rear elevational view thereof on a slightly larger scale;

FIG. 4 is a top plan view thereof on a slightly larger scale, the bottom being a mirror image; and

FIG. 5 is a side elevational view thereof on a slightly larger scale, the opposite side being a mirror image.

FIG. 1

FIG. 4

FIG. 2

FIG. 5

FIG. 3
